UNITED STATES PATENT OFFICE.

FREDERICK W. CHESSON, OF WATERBURY, CONNECTICUT, ASSIGNOR TO
THE AMERICAN RING COMPANY, OF SAME PLACE.

DESIGN FOR A METAL MOUNT.

SPECIFICATION forming part of Design No. 27,510, dated August 10, 1897.

Application filed December 26, 1896. Serial No. 617,113. Term of patent 7 years.

To all whom it may concern:

Be it known that I, FREDERICK W. CHESSON, a citizen of the United States, residing at Waterbury, in the county of New Haven and State 5 of Connecticut, have invented and produced a new and original Design for Metal Mounts, of which the following is a specification, reference being had to the accompanying drawings, in which—

10 Figure 1 is an elevation, and Fig. 2 a plan, of my design.

The general configuration of the metal mount is round; and the leading features of my design consist in the convex body portion 15 having semicircular ribs placed circumferentially and in lines parallel with the axis, the adjacent bands, and contracted or coved portions.

The convex body portion is shown at *a*, the top and bottom bands at *b b'*, the coved contracted portion at *c*, the cove at *c'*, the bead at *d*, and the large convex body portion at *e*. The convexed body portions (shown at *a* and *e*) are ornamented with semicircular ribs placed circumferentially and in lines parallel 25 with the axis of the mount.

What I claim is—

The design for a metal mount, substantially as shown and described.

Signed by me this 17th day of December, 30
A. D. 1896.

F. W. CHESSON.
